JAMES E. WHYTE AND DUNCAN McAULAY, OF NIAGARA FALLS, NEW YORK; SAID
McAULAY ASSIGNOR TO SAID WHYTE.

MAGAZINE AND NEWSPAPER RACK.

Application filed September 16, 1926. Serial No. 135,902.

Our invention relates to improvements in magazine and newspaper racks, and it has for one of its objects the production of a rack of this kind in which magazines or 5 newspapers may be arranged systematically so that the headings or titles thereof will be displayed, the magazines or newspapers being loosely retained so that they can be easily withdrawn from the rack.

10 Another object of our invention is to provide a rack of this kind which is simple in construction, comparatively inexpensive, and which can be conveniently carried from place to place so that it can be placed outside of stands or shops during business hours and stored within a stand or taken into a shop after such hours.

Another object is to provide a rack of this kind in which the individual retainer elements are constructed so that one is utilized 20 to fasten another in place.

A still further object is to provide a suitable support for the rack and to construct the retainer elements, in preferred form, of 25 wire, with the ends of the wire fastened to or into the support and incidentally serving to fasten one end of an adjacent retainer element to said support.

With the above and other objects in view 30 to appear hereinafter, the invention consists in the novel features of construction and in the arrangement and combination of parts to be hereinafter described and more particularly pointed out in the subjoined claims.

In the drawings,—

Fig. 1 is a front elevation of our improved rack.

Fig. 2 is a side elevation thereof, parts of 40 which are broken away to show the manner of fastening the upper ends of certain retainer elements against the support.

Fig. 3 is a perspective view of the rack with magazines inserted in the retainer elements.

Fig. 4 is a detached perspective view of one of the retainer elements.

Fig. 5 is a cross section taken on line 5-5, Fig. 1.

Fig. 6 is a longitudinal section taken on line 6-6, Fig. 1.

Fig. 7 is a detached perspective view of the hanger, which incidentally serves to fasten the upper end of the uppermost retainer element to the support.

Fig. 8 is a detached perspective view of the fastener element whereby the upper end of the second retainer element is secured to the support.

Reference being had to the drawings in detail, the numeral 10 designates the support, on which the retainer elements are systematically arranged and to which they are fastened. This support is preferably in the form of a narrow board along which the retainer elements are arranged, and in the construction shown, representing one embodiment of our invention, these retainer elements are arranged one above the other.

Each of the retainer elements, designated by the numeral 11, is formed of wire bent to provide a transverse central member 12, at opposite ends of which the wires are bent forwardly, as at 13 and thence inwardly toward the vertical center thereof, as at 14, forming a substantially open loop at the upper end of the retainer. From the inner ends of these inwardly-bent portions 14 the wire is directed downwardly in converging planes, as at 15, and at the lower end thereof rearwardly, as at 16, thence inwardly, as at 17, and finally forwardly, as at 18, the latter forming the fastening portions for the retainer elements and incidentally serving to fasten the upper end of the second retainer element below.

The hanger, as best shown in Fig. 7, is formed of wire bent between its ends to form an open loop 19, the lower ends of the wire being directed forwardly, as at 20, for a purpose to appear hereinafter.

The fastener for fastening the upper end of the second retainer element to the support or foundation is in the form of an elongated staple, as clearly shown in Fig. 8, and is designated by the numeral 21.

The retainer elements are arranged so that one overlies another and they are applied to the front of the support 10, the transverse central member 12 of each lying crosswise in contact with the front face of the support or foundation.

At regular intervals along the length of the support or foundation, two parallel rows of holes 22 are provided, the holes being arranged in pairs, and through the lowermost pair of holes 22 the forwardly bent portions 18 of the lowermost fastening element are passed from the rear of the support. To accomplish this, the retainer element is po-

sitioned so that the inwardly-bent portions 17 lie against the rear surface of the support, while the rearwardly bent portions 16 thereof lie against the edges of said support. 5 The projecting ends of the forwardly-bent portions 18 are bent downwardly against the front of the support or foundation, as at 23.

In placing the lowermost retainer element 10 in position, the upper end thereof is arranged in front of the support or foundation, with the transverse central member lying crosswise and directly beneath the third lowermost pair of holes 22 in said support or foundation. The rearwardly-bent portions 16 are somewhat longer than the thickness of the support 10 so that they reach forwardly to a plane in advance of the front surface of said support and serve as 20 rests for the newspapers or magazines placed within the retainer, as clearly shown in Figs. 2 and 3.

The remaining retainer elements are similarly arranged on and fastened to the support, with the exception that the forwardly-bent portions 18 of all retainer elements above the second lowest have their extremities bent over the transverse central members 12 of a lower retainer element, as shown at 25 30 35 40 45 50 55 60 65 70 75 80 85 90 95 100 105 110 115 120 125

24, thus serving to fasten the upper ends of the last-mentioned retainer element to the support and at the same time serving to fasten the lower end of the retainer element of which it forms part, against said support.

35 The upper end of the second retainer element is fastened to the support by means of the staple 21, the parallel free ends of which are passed through the second pair of holes 22 in said support and are bent over the transverse central member 12 of said second retainer element.

40 The upper end of the uppermost retainer element is fastened to the support by means of the hanger 19 which is placed against the rear surface of the support and has its loop 45 projecting upwardly therefrom, while the extremities 20 thereof are passed through the uppermost pair of holes 22 in the support and bent over the transverse central member 12 of said uppermost retainer element.

45 The downwardly converging members 15 and the inwardly-bent portions 14 of the wire prevent forward tipping of the newspapers or magazines placed within the retainer, and these downwardly converging members 15, with the open loop wire construction at the upper end thereof, form an open pocket into which newspapers or magazines can be conveniently placed, the rearwardly-bent portions 16 forming rests for the newspapers or magazines at the lower ends of the pockets.

50 By reason of the fact that the members 15 are made to converge downwardly and overlie the transverse central member 12 of

the wire retainer element next below, the retainer elements may be said to taper downwardly and be nested one within the other so that newspapers and magazines placed within said retainer elements, or more particularly the pockets thereof, will be displayed in overlapping relation, the lowermost having its front page or cover fully exposed, while the remaining newspapers or magazines have only the upper portions exposed to display the heading or titles thereof. In this manner, a compact construction is provided, enabling a comparatively large number of newspapers or magazines to be displayed within a comparatively small space. 70 75 80

Having thus described our invention, what we claim is:—

1. A rack of the kind described, comprising an elongated support having a plurality of holes formed therethrough, retainer elements formed of wire, each arranged with one end against one side of said support and with its other end against the opposite side thereof, said last-mentioned end having free terminals passed through certain of said holes and serving to fasten the first-mentioned end of another retainer element to said support. 85 90

95 100 105 110 115 120 125

2. A rack of the kind described, comprising an elongated support having a plurality of pairs of holes formed therethrough, retainer elements formed of wire and arranged one above another on said support, each retainer element having a transverse member at one end extending across said support and free terminals at its lower end passed through a pair of said holes, the free terminals or certain retainer elements being bent over the transverse members of alternate retainer elements.

3. A rack of the kind described, comprising a support having a plurality of pairs of holes therethrough, a series of retainer elements arranged along said support, each retainer element being formed of wire bent to form a retainer pocket and a rest at the lower end of said retainer pocket and having free terminals at its lower end passed through a pair of holes in said support from the rear thereof, the upper end of said retainer pocket including a transverse member lying against the front of said support and having the extremities of the free terminal of another member bent over the same to fasten it to said support. 110 115 120

4. A rack of the kind described, comprising an elongated support provided with a pair of holes near its upper end, retainer elements arranged along said support in overlapping relation, a loop applied to the rear surface of said support and extending above the upper end thereof, said loop having free terminals passed through said pair of holes and engaging the upper end 125 130

of the uppermost retainer element to fasten the same in position.

5. A rack of the kind described, comprising an elongated support having a plurality of pairs of holes formed along the same in spaced relation, retainer elements formed of wire having free terminals at their lower ends passed through certain of said pairs of holes and being bent to hold the same in position and incidentally fasten the upper ends of certain retainer elements to said support, a staple having free terminals passed through one of said pairs of holes and being bent to fasten the upper end of one of said retainer elements to said support, and a hanger in the form of a loop having free terminals passed through the uppermost pair of holes in said support and being bent to fasten the upper end of the uppermost retainer element to said support.
6. A rack of the kind described, comprising an elongated support having a plurality of pairs of holes formed therethrough and arranged in spaced relation, a series of retainer elements applied to said support with their lower ends against the rear surface thereof and their upper ends against the front surface thereof, each of said retainer

elements being formed of a length of wire bent centrally between its ends to form a transverse central member and forwardly extending portions at opposite ends of said central member, said wire being bent inwardly from the forward ends of said forwardly bent portions and thence direct downwardly in converging lines to form an open pocket, said wire being bent rearwardly at the lower ends of said downwardly converging portions to form rests for magazines or newspapers and lying with their rear portions against opposite edges of said support, said wire being thence bent inwardly to lie against the rear face of said support and finally forwardly to extend through a pair of holes in said support, the extremities of certain of said forwardly bent portions being bent around the central transverse member of another retainer element, and means for independently fastening the transverse central members of the two uppermost retainer elements to the front of said support.

In testimony whereof I affix my signature.

JAMES E. WHYTE.
DUNCAN McAULAY.
